UNITED STATES PATENT OFFICE

1,947,022

MINER'S LAMP

Otto Schneider, Dresden, Germany, assignor, by
mesne assignments, to Marshall Van Winkle,
Jr., Jersey City, N. J.

Application November 4, 1930, Serial No. 493,318,
and in Germany November 15, 1929

12 Claims. (Cl. 240—11.3)

Miners' lamps should be made very strong and durable because of the severe usage to which they are subjected. These lamps should also be capable of being readily taken apart and reassembled. Their illumination should also be of the best and so far as possible the dark shadows eliminated so that the work may be well lighted. Also, the character of the illumination should be such as not to blind or subject the miner to severe eye strain. The lamp should also be free from any danger of short circuit.

The present invention is directed generally to providing a miner's lamp which will successfully meet the above requirements and consists in certain improvements in the construction, form and arrangement of the several parts of the lamp which will be hereinafter pointed out and claimed.

In miners' lamps as heretofore produced the lower member of the lamp served as the accumulator container and was usually covered on one face with a film or sheet of lead. Lamps of this kind were, however, not safe in use because short circuits easily occurred when the lamps were subjected to rough usage. In order to avoid the above named disadvantage, one object of my invention is to provide a separate accumulator container of insulating material properly positioned within an outer container, said accumulator container being sealed by a removable cover so that access to the accumulator may be readily gained without damaging the accumulator or the container within which it is housed.

Furthermore, in miners' lamps now in use the incandescent bulb is usually covered by a clear or frosted glass dome serving as a protector for the bulb. Lamps of this kind are, however, unsatisfactory because of the liability of the glare to adversely affect the eyes of the miner. Another object of my invention, therefore, is to provide a glass protector for the incandescent lamp bulb of such a character that a homogeneous light is given off, such object being accomplished by the provision of an opalescent glass either in the form of the protector itself or in the form of a lamina therefor or in the form of a separate protector inside a protector of transparent glass.

A further object also is the provision of reflectors for the lamp so arranged as to improve the lighting effect of the lamp and to prevent the formation of shadows thereby.

A practical embodiment of my invention is represented in the accompanying drawing, in which

Fig. 1 represents the lamp in side elevation, partly in section;

Fig. 2 represents a vertical central section taken

in the plane of the line II—II of Fig. 1, looking in the direction of the arrows, and

Fig. 3 represents a glass protector of modified form.

The lower member of the lamp is shown as 60 comprising an outer container 1 within which is located an inner container 2 for the accumulator 3. This inner container is made of some suitable insulating material. The outer container 1 is provided with an inner annular shoulder 4 65 which forms a seat for an outer annular shoulder 5 on the inner container. This inner container is also provided with an inner annular shoulder 6 which forms a seat for a yielding gasket 7 on which rests the cover 8 for the inner 70 container. A liquid tight seal is provided between the cover 8 and the inner container by providing a removable locking ring 9 which has a screw threaded engagement with the inner wall of the outer container and presses against 75 the top of the cover 8.

The upper portion of the lamp is shown as having a base 10 which has a screw threaded engagement with the outer container 1. Spaced 80 projecting bars 11 arise from the base 10 and are provided at their tops with a canopy 12 which carries the suspension eye 13.

The incandescent lamp bulb 14 is removably secured in its socket 15 uprising from a disc 16 of insulating material, the bottom of which disc 85 is provided with conducting plates 17, 18, arranged to be brought into and out of contact with the terminals 19, 20 of the positive and negative electrodes of the accumulator 3, as the upper member of the lamp is turned on its lower 90 member.

A glass protector in the form of a dome is provided for the incandescent lamp bulb 14, which protector is herein shown as mounted upon the disc 16. These protectors have usually been of 95 clear or frosted glass and were unsatisfactory because of the glare. To prevent this glare I have shown this protector as having incorporated therein opalescent glass. In the form shown in Fig. 2 the protector comprises an outer clear 100 or transparent lamina 21 and an inner opalescent lamina 22. These two laminae may be unitary or separate, as desired or the entire protector may be made of opalescent glass, as indicated in Fig. 3.

To improve the lighting effect of the lamp and to prevent the formation of shadows I have provided reflectors therefor as follows: A reflector 23 surrounds the base of the incandescent lamp bulb 14 within the glass protector, which 110

reflector is shown as being provided with a flange 24 secured to the disc 16. Another reflector 25 preferably of concave form substantially following the curve of the top of the protector is located between the top of the reflector and the underside of the canopy 12. In the present instance this reflector is shown as a lining for the bottom of the canopy and as having an extended lateral flange 26 beyond the concave portion of the reflector.

10 The upper portion of the lamp may be held in its on or off position by providing two recesses 27, 28 in the lower member and a spring plunger latch 29 carried by the upper member of the lamp.

15 It is evident that various changes may be resorted to in the construction, form and arrangement of the several parts without departing from the spirit and scope of my invention, and hence 20 I do not intend to limit myself to the particular embodiment herein shown and described, but

What I claim is:—

25 1. A miner's lamp including an accumulator, outer and inner containers having coating inner and outer shoulders for suspending the inner container in spaced relation with respect to the outer container, said inner container being of insulating material and housing the accumulator.

30 2. A miner's lamp including an accumulator, outer and inner containers having coating inner and outer shoulders for suspending the inner container in spaced relation with respect to the outer container, said inner container being of insulating material and housing the accumulator, and a removable cover disposed within the outer container for sealing the inner container.

35 3. A miner's lamp including an accumulator, outer and inner containers having coating inner and outer shoulders for suspending the inner container in spaced relation with respect to the outer container, said inner container being of insulating material and housing the accumulator, a removable cover disposed within the outer container for sealing the inner container, and means engaging the interior wall of the outer container for tightening the cover on its container.

40 4. A miner's lamp including an accumulator, outer and inner containers, said inner container being of insulating material and housing the accumulator, a removable cover disposed within the outer container for sealing the inner container, and a removable locking ring having a screw threaded engagement with the interior wall of the outer container for tightening the cover on the inner container.

45 5. A miner's lamp including an accumulator, outer and inner containers having coating inner and outer shoulders for suspending the inner container in spaced relation with respect to the outer container, said inner container being of insulating material and housing the accumulator, a removable cover disposed within the outer container for sealing the inner container, and a removable locking ring having a screw threaded engagement with the interior wall of the outer container for tightening the cover on the inner container.

6. A miner's lamp including an accumulator, outer and inner containers, said inner container being of insulating material and housing the accumulator, a removable cover disposed within the outer container for sealing the inner container, a removable locking ring having a screw threaded engagement with the interior wall of the outer container for tightening the cover on the inner container, and a yielding gasket interposed between the cover and its container.

80 7. A miner's lamp including an accumulator, outer and inner containers having coating inner and outer shoulders for suspending the inner container in spaced relation with respect to the outer container, said inner container being of insulating material and housing the accumulator, a removable cover disposed within the outer container for sealing the inner container, a removable locking ring having a screw threaded engagement with the interior wall of the outer container for tightening the cover on the inner container, and a yielding gasket interposed between the cover and the inner shoulder of its container.

90 8. In a miner's lamp, an incandescent lamp bulb, an opalescent glass protector therefor having a dome-shaped top, and a concave reflector spaced above the top of the protector and conforming substantially to the curve of the top of the protector.

95 9. In a miner's lamp, an incandescent lamp bulb, an opalescent glass protector therefor having a dome-shaped top, a cylindrical reflector surrounding the base of the bulb within the protector, and a concave reflector spaced above the top of the protector and conforming substantially to the curve of the top of the protector.

105 10. In a miner's lamp, an incandescent lamp bulb, an opalescent glass protector therefor having a dome-shaped top, and a canopy spaced above the top of the protector, the bottom of said canopy being provided with reflecting surfaces of different forms, one of said surfaces extending outwardly beyond the vertical plane of the protector.

110 11. In a miner's lamp, an incandescent lamp bulb, an opalescent glass protector therefor having a dome-shaped top, and a canopy spaced above the top of the protector, said canopy being provided with a concave central reflecting surface conforming substantially to the curve of the top of the protector and a straight peripheral reflecting surface, said straight surface extending outwardly beyond the vertical plane of the protector.

115 12. In a miner's lamp, an incandescent lamp bulb, an opalescent glass protector therefor having a dome-shaped top, and a canopy spaced above the top of the protector, the bottom of said canopy being provided with a lining, said lining comprising a concave central reflecting surface conforming substantially to the curve of the top of the protector and a straight peripheral reflecting surface extending outwardly beyond the vertical plane of the protector.

120 130

OTTO SCHNEIDER.
